UNITED STATES PATENT OFFICE

140,792

DESIGN FOR A COMBINED FINGER GRATE AND BURNER BOWL

Eugene L. Baker, Taunton, Mass.

Application April 18, 1944, Serial No. 113,292

Term of patent 14 years

(Cl. D81—25)

To all whom it may concern:

Be it known that I, Eugene L. Baker, a citizen of the United States, residing at Taunton, in the county of Bristol and Commonwealth of Massachusetts, have invented a new, original, and ornamental Design for Combined Finger Grate and Burner Bowl, of which the following is a specification, reference being had to the accompanying drawing, forming a part thereof, in which:

Fig. 1 is a view in perspective of a combined finger grate and burner bowl showing my new design; and

Fig. 2 is a cross-sectional view on the line II—II of Fig. 1.

I claim:

The ornamental design for a combined finger grate and burner bowl, substantially as shown.

EUGENE L. BAKER.
